UNITED STATES PATENT OFFICE.

JOHN REYNOLDS, OF MONTCLAIR, NEW JERSEY, ASSIGNOR TO THE SOUTHWICHINGON HARDWARE CO., OF SOUTHWICHINGON, CONNECTICUT, A CORPORATION.

DESIGN FOR A PUTTY KNIFE OR SIMILAR ARTICLE.

Application filed December 12, 1927. Serial No. 24,447. Term of patent 7 years.

To all whom it may concern:

Be it known that I, JOHN REYNOLDS, a citizen of the United States, residing at Montclair, in the county of Essex and State of New Jersey, have invented a new, original, and ornamental Design for a Putty Knife or Similar Article, of which the following is a specification, reference being had to the accompanying drawing, forming part thereof.

The appearance of the handle is the dominant feature of the design.

Fig. 1 is a front elevation of a putty knife showing my new design; and

Fig. 2 is a side view of the same.

I claim:

The ornamental design for a putty knife or similar article as shown and described.

JOHN REYNOLDS.
